(57) **CLAIM**

The ornamental design for a thermal conduction metal material, as shown and described.

DESCRIPTION

FIG. 1 is a perspective view from the top and left side of thermal conduction metal material.

FIG. 2 is a perspective view from the bottom and left side thereof.

FIG. 3 is a perspective view from the top and right side thereof.

FIG. 4 is a top plan view thereof.

FIG. 5 is a bottom plan view thereof.

FIG. 6 is a front elevation view thereof.

FIG. 7 is a rear elevation view thereof.

FIG. 8 is a left side elevation view thereof.

FIG. 9 is a right side elevation view thereof.

FIG. 10 is an enlarged cross-sectional view taken along the line 10-10 in the FIG. 4.

FIG. 11 is an enlarged cross-sectional view taken along the line 11-11 in the FIG. 4.

FIG. 12 is an enlarged cross-sectional view taken along the line 12-12 in the FIG. 4; and,

FIG. 13 is an enlarged cross-sectional view taken along the line 13-13 in the FIG. 4.

The design shown is not to be limited to any particular size and may be scaled larger or smaller.
